BY

Walter A. Knight
ATTORNEY

UNITED STATES PATENT OFFICE.

LINNAEUS E. BAKER, OF FORT WAYNE, INDIANA, ASSIGNOR TO WAYNE COMPANY, OF FORT WAYNE, INDIANA, A CORPORATION OF INDIANA.

SAFETY MECHANISM FOR DISPENSING APPARATUS.

Application filed April 19, 1924. Serial No. 707,704.

My invention relates to safety mechanism for visible gasolene dispensing apparatus.

The particular object of my invention is to render the pump incapable of delivering 5 gasolene into the overhead visible container when the mechanism for draining back the contents of said container has been set in drain-back position.

When set in drain-back position a passage 10 is opened to admit air from the visible container to the suction side of the pump which is used to fill said container, rendering the pump incapable of drawing gasolene from the storage tank below. When the drain-back mechanism is so set it may be locked rendering the pump incapable of elevating 15 gasolene until the drain-back valve is unlocked and closed.

When the drain-back valve mechanism is 20 unlocked and the drain-back valve closed, the passage to the suction side of the pump is also closed. Then the apparatus is ready for use to both pump and serve gasolene.

In the particular embodiment of my invention selected for illustration:

Figure 1 is a visible gasolene dispensing apparatus and tank, part of the tank being broken away to show the foot valve; the pump casing, visible container and drain 30 back valve mechanism and connections being shown in vertical axial section;

Fig. 2, a detail, is a similar view of the drain-back valve and connections, the overflow pipe being broken away to show the 35 drain-back pipe and the fill-pipe removed;

Fig. 3, a detail, is a vertical view of the pump, the cover plate being removed and part of the casing being broken away and in section;

Fig. 4, a detail, is a front view of the lock and the drain-back valve showing the operating lever locked in drain-back position;

Fig. 5, a detail, is an enlarged sectional view of valve and casing on line 5-5 of Fig. 2 as though there shown in full, the valve being shown open, and

Fig. 6 is the same with the valve shown closed.

Referring now to the drawings, T is a 50 gasolene storage tank buried under the sidewalk S, with foot valve t connected to the outlet suction pipe t¹ and overflow pipe t². Pipes t¹ and t² extend upwardly through

55 the sidewalk into the casing C, within which

is the pump P and surmounting which is the container G of glass or other transparent material, with cap g.

At the top of the suction pipe t¹ is placed any suitable pump P, the one shown being a 60 rotary pump of the usual type, adapted to force the gasolene through the fill-pipe t³ into the visible container G. The overflow pipe t² terminates at such a height within the visible container G as to drain back to the tank T at each filling any gasolene in the container G in excess of the full number of units of measure, as five or ten gallons, that the container is adapted to dispense when substantially full. The pipes 65 t² and t³ have no valves but are open at all times. A valve E is adapted to open and close an outlet from the container G, through which the gasolene flows to the 70 automobile tanks or other receptacles of purchasers.

A drain D leading from the floor of the container G to the overflow pipe t² is also connected by a pipe d with the suction side 75 of the pump P. A valve d¹ is adapted to close the drain so that no liquid will flow from the container G through the drain either to the pipe t² or the pipe d. A lock d² is adapted to lock the valve d¹ when it is adjusted to drain-back position which is 80 open position.

Whenever the dispensing apparatus is 85 shut down as at night the gasolene in the container G is drained back to the tank T as a precaution against fire. This draining is accomplished by opening the valve d¹ and locking it in open position. The gasolene in the container G then flows through the drain D to the overflow pipe t² and thence to the storage tank T.

If when so shut down some meddlesome person attempts to operate the pump P, it will not pump liquid because the gasolene in d will be drained out by the operation of the pump and then air will pass into the suction side of the pump, immediately rendering it useless for pumping until the valve d¹ is closed.

Many changes may be made in my improvement from that herein shown and described without departing from the spirit of my invention, and I claim as covered hereby any apparatus readable upon the claims ultimately allowed hereon.

I claim as my invention and desire to

secure by Letters Patent of the United States:—

- 5 1. In combination with a dispensing apparatus having a storage tank below, a dispensing container above, a fill pipe connecting said tank and said container, a foot valve for said fill pipe, a suction pump in said fill pipe line, means independent of said fill pipe line for draining the contents of said container back to said tank; and a valved fluid by-pass between said means and the suction side of said pump.
- 10 2. In combination with a dispensing apparatus having a storage tank below, a dispensing container above, a fill pipe connecting said tank and said container, a foot valve for said fill pipe, a suction pump in said fill pipe line, means independent of said fill pipe line for draining the contents of said container back to said tank; a valved fluid by-pass between said means and the suction side of said pump, and means for opening and closing said draining means and said valved fluid by-pass.
- 15 3. In combination with a dispensing apparatus having a storage tank below, a dispensing container above, a fill pipe connecting said tank and said container, a foot valve for said fill pipe, a suction pump in said fill pipe line, means independent of said fill pipe line for draining the contents of said container back to said tank; a valved fluid by-pass between said means and the suction side of said pump and unitary means for opening and closing said draining means and said valved fluid by-pass.
- 20 4. In combination with a dispensing apparatus having a storage tank below, a dispensing container above, a fill pipe connecting said tank and said container, a foot valve for said fill pipe, a suction pump in said fill pipe line, an overflow pipe connecting said container with said tank, a valve in said overflow pipe, a valved fluid by-pass from said valve in said overflow pipe to the suction side of said pump, said valve in said by-pass adapted to close fluid communication in said by-pass and said overflow pipe simultaneously, and to open fluid communication in said by-pass and said overflow pipe simultaneously.
- 25 5. In combination with a gasoline dispensing apparatus having a storage tank below, a dispensing container above, a fill pipe connecting said tank and said container, a foot valve for said fill pipe, a suction pump in said fill pipe line, an overflow pipe connecting said container with said tank, a valve in said overflow pipe, a valved fluid by-pass from said valve in said overflow pipe to the suction side of said pump, said valve in said by-pass adapted to close fluid communication in said by-pass and said overflow pipe simultaneously, and to open fluid communication in said by-pass and said overflow pipe simultaneously.
- 30 6. In combination with a gasolene dispensing apparatus having a storage tank below, a dispensing container above, a fill pipe connecting said tank and said container, a foot valve for said fill pipe, a suction pump in said fill pipe line, an overflow pipe connecting said container with said tank, a valve in said overflow pipe, a valved fluid by-pass from said valve in said overflow pipe to the suction side of said pump, said valve in said by-pass adapted to close fluid communication in said by-pass and said overflow pipe simultaneously, and to open fluid communication in said by-pass and said overflow pipe simultaneously and means for locking said valve in open position.

In testimony whereof I have hereunto set my hand.

LINNAEUS E. BAKER.
